Philip C. Curtis, Scottsdale, Ariz.

Application October 14, 1953, Serial No. 27,174

Term of patent 3½ years

(Cl. D33—14)

To all whom it may concern:

Be it known that I, Philip C. Curtis, a citizen of the United States, residing at Scottsdale, county of Maricopa, and State of Arizona, have invented a new, original, and ornamental Design for a Table, of which the following is a specification, reference being had to the accompanying drawing, forming a part hereof.

Fig. 1 is a prospective view of a table showing my new design; and

Fig. 2 is a prospective view of the underneath portion of the table.

I claim:

The ornamental design for a table, substantially as shown.

PHILIP C. CURTIS.
